CLAIM

The ornamental design for a hand tool, as shown and described.

DESCRIPTION

FIG. 1 is a front view of a hand tool with a portion of the hand tool extended in accordance with my invention; FIG. 2 is a back view of the hand tool with a portion of the hand tool extended;

FIG. 3 is a back view of the hand tool with a portion of the hand tool retracted;

FIG. 4 is a front view of the hand tool with a portion of the hand tool retracted;

FIG. 5 is a perspective top view of the hand tool with a portion of the hand tool extended;

FIG. 6 is a perspective top view of the hand tool with a portion of the hand tool retracted; and,

FIG. 7 is a bottom view of the hand tool with a portion of the hand tool extended.
